Primary Examiner — Catherine S Posthauer

Assistant Examiner — Joan E. Diehl

(74) Attorney, Agent, or Firm — PEARL COHEN
ZEDEK LATZER BARATZ LLP(57) **CLAIM**

The ornamental design for a bottle as shown and described.

DESCRIPTION

1.1 : Front

1.2 : Top

1.3 : Bottom

1.4 : Perspective

The shading in the reproductions represent contours and do not illustrate an ornamentation or decoration on the surface of the product. The parts shown by means of broken lines in the reproductions are not part of the claimed design. The front view is identical to all other side views.

1 Claim, 4 Drawing Sheets(56)
